UNITED STATES PATENT OFFICE

139,318

DESIGN FOR A FLOWERPOT HOLDER

Frank Cardelli, Hot Springs, Ark.

Application July 31, 1944, Serial No. 114,653

Term of patent 7 years

(Cl. D35—3)

To all whom it may concern:

Be it known that I, Frank Cardelli, a citizen of the United States, residing at 128½ Oak Street, in the city of Hot Springs, county of Garland, and State of Arkansas, have invented a new, original, and ornamental Design for a Flowerpot Holder, of which the following is a specification, reference being had to the accompanying drawing, forming a part thereof.

Fig. 1 is a perspective view of a flowerpot holder embodying my new design.

Fig. 2 is a side elevational view of the same.

Fig. 3 is a top plan view of the same.

I claim:

The ornamental design for a flowerpot holder, substantially as shown.

FRANK CARDELLI.
